GEORGE A. BELDING, OF PITTSBURGH, PENNSYLVANIA, ASSIGNOR TO ALUMINUM COMPANY OF AMERICA, OF PITTSBURGH, PENNSYLVANIA, A CORPORATION OF PENNSYLVANIA

MEANS FOR FASTENING CORRUGATED SHEETS AND THE LIKE

Application filed August 2, 1929. Serial No. 383,110.

This invention relates to means for fastening or connecting corrugated or flat roofing sheets or siding sheets to structural elements, such as beams, purlins, girders and the like.

5 Prior to this invention, sheet metal roofing and siding sheets, either plain or corrugated, were connected or attached to structural elements, such as purlins, rafters, beams, girders and the like, by means of two common types 10 of fastening devices. One type consisted of a pair of headed members passing through the material to be fastened and around the structural element to which it was to be secured, the free ends thereof being twisted together 15 preferably beneath the lower flange of the purlin. In the other type of fastener, two headed members were also used. One of the headed members, however, was provided with a bight at any desired point whereby, after 20 the ends of the two members were twisted together as above mentioned, any looseness could be taken up by twisting the bight. Both of these types, by reason of the two headed members, made it necessary to form two holes 25 in the material to be secured. Also, due to the fact that two headed members were used, a uniform tension in both members could not be obtained and there frequently resulted an undesirable looseness.

30 I have found that with a fastening device comprising a headed member fastened through a single hole in the material to be secured and cooperating with a flexible pliable material adapted to be secured to the 35 structural element, I can provide a fastening device which in addition to being simple and easy to apply and remove eliminates one hole through the material to be secured and is substantially free from any looseness.

40 It is therefore an object of this invention to provide means for fastening corrugated sheets or sidings to structural elements comprising a single means passing through said sheets and means cooperating therewith to 45 fasten said first named means to said structural element.

Another object of this invention is to provide a device for fastening a sheet of material to a structural element comprising a 50 headed member passing through said sheet

and provided with a hole in the shank thereof and a member formed of a pliable material adapted to pass through said hole and be secured in such a manner that it will pass around the structural element.

Other objects of this invention will appear from the following description, appended claim and accompanying drawings in which:

Figure 1 illustrates the fastening device constituting this invention, the sheet and structural element being shown in section.

Figure 2 is an end view of Figure 1.

Referring to the drawings in which like reference numerals designate like parts, the reference numeral 1 designates corrugated 65 sheets adapted to form a roofing or siding, disposed on purlins 2 or other structural elements. A headed member 3 extends through a hole 4 formed in the corrugated material. The shank of the member 3 is provided with 70 a hole 5 through which a flexible pliable member 6 is adapted to pass. The ends 7 of the member 6 are brought together and twisted beneath the lower flange of the purlin 2, as indicated at 8, forming a strap 75 embracing the purlin and securing the headed member to the corrugated sheet. By reason of this construction, the flexible member adjusts itself during the twisting of the ends thereof so that a secure fastening, substantially devoid of any looseness, is obtained.

The flexible member 6 may be a wire formed of a solid piece of suitable material, such as annealed iron, soft drawn copper or aluminum, of such a character that it will resist 85 considerable strain and will permit the ends thereof to be readily twisted together.

The ends 7 of the member 6 are indicated in the drawings as being brought together beneath the lower flange of the purlin. It 90 is to be understood that the ends 7 of the member 6 may be twisted together at other positions than the one indicated, though the latter is preferable.

The headed member 3 may be disposed in 95 any desired position. Preferably, it is so positioned that the member 6 is formed with the least number of bends therein. To attain the latter the headed member 3 is usually disposed in line with one of the edges of the 100

purlin as illustrated. In practice, it is usual to dispose a gasket 9 between the head 10 of the headed member 3 and the corrugated sheet 1.

5 The headed member 3 may be a rivet, bolt, pin or the like. The head 10 thereof may be formed of any suitable design. It may have a curved top and a flat bottom or it may be made so as to conform to the shape of the corrugated material.

10 The fastening means above described is simple and efficient. It is easy to apply and remove, if desired. The fastener is capable of giving a direct pull on the sheet to be secured. Due to the structure and location of 15 the cooperating parts, a fastener substantially free from looseness is obtained.

I claim:

20 A device for fastening a sheet of material to a structural element comprising a headed member passing through said sheet and having a hole in the shank thereof, a wire passing through said hole and around said structural element, said wire having its ends 25 twisted together whereby a strap is formed, said headed member being so disposed as to form the least number of bends in said wire.

In testimony whereof, I have affixed my signature to this specification.

GEORGE A. BELDING.
